UNITED STATES PATENT OFFICE.

PAUL WARE, OF NEW YORK, N. Y., ASSIGNOR TO WARE RADIO, INC., OF NEW YORK,
N. Y., A CORPORATION OF DELAWARE.

DUPLEX CUT-IN SYSTEM OF RADIOTELEGRAPHY.

Original application filed February 8, 1918, Serial No. 215,996, Patent No. 1,379,144. Divided and this application filed April 14, 1921. Serial No. 461,436.

This invention relates to radio telegraphy and has for its object to increase the rapidity with which traffic may be handled by enabling the receiving station to cut in on the sending station at will and without disturbing the adjustments of the system.

Much delay is now caused in radio telegraph communication because the receiving operator must wait until the sending operator has signed off before he can communicate with the sending operator. By this invention, the receiving operator can cut in on the sending operator at any time, so that it becomes unnecessary for the receiving operator to wait until the sending operator has signed off and has put his apparatus in condition for receiving, and the receiving operator has put his apparatus in condition for sending, before reversing the direction of communication. This invention is especially adapted for undamped wave transmission by the beats method, wherein the frequencies of the sending and receiving stations differ to such extent that beats are produced at the receiving station. In present methods of radio telegraphy by the beats method, the sending operator does not hear the beat note, and consequently does not know either whether his signals are being sent out from his station, the character of his sending, or whether they are being received at the other end, which is the reason for much of the delay above referred to, but with this invention signals may be produced and simultaneously controlled at both ends.

According to this invention, a station is provided for long distance communication wherein a relatively powerful transmitting set is separated a sufficient distance from the receiving set so that the latter is not paralyzed by the former. The operator is usually stationed at the receiving set and his key controls the transmitter by means of a relay or other suitable means.

In normal operation of such a station embodying a preferred form of this invention the receiving set is continuously oscillating on one frequency and coupled to a collecting device, such as an antenna, receiving incoming oscillations of sufficient difference in frequency as to produce a beat note in the receiving set which is detected by suitable means. This receiving set is connected to the sending key in such manner that the

key has a normal position for receiving and another position wherein it suppresses or changes the pitch of the signal beat note in the receiving set and at the same time suppresses or changes the outgoing oscillations from the sending set so that at the other station the signal beat note is also suppressed or changed in pitch, to effect the signal. However, cut in can still be effected if the local receiving set is not affected by the sending key, but much less advantageously because the sending operator cannot hear his own telegraphing. With this invention the operator is enabled to listen to his own sending on the same signal device as he receives with, and produced in the same manner. This is electrically similar to the method employed in wire telegraphy.

In the specific embodiment such a system is characterized by signal beat notes being continuously produced at each station when the keys are in like (send-receive) position, and the actuation of either key suppressing or varying both beat notes. The incoming message is thus produced by the sending operator actuating his key in the usual manner while the receiving operator holds his key in receiving position, and when the latter desires to cut in he simply throws his key to the other position suppressing both beat notes and thereby making a signal to the sending operator who will thereupon place his key in receiving position to receive the message which he expects from the receiving operator. Each operator also hears his own message.

The accompanying drawing shows in diagram a form of apparatus embodying the invention, wherein there is such distance between the receiving and sending set as to prevent the latter paralyzing or affecting the former, enabling strong outgoing oscillations to be sent for the desired distance.

1 represents a sending antenna having inductance 2 and condenser 3 leading to ground 4. The source of powerful sending oscillations is tube 6 wherein plate 7 is connected by wire 8 to inductance 9 coupled to inductance 2 thence by wire 10 to power battery 11, ammeter 12 and wire 13 to wire 14. The wire 14 is connected to filament 15 thence to filament resistance 16 and filament heating battery 17. The grid 18 is connected by wire 19 to inductance 20 also coupled

to inductance 2 thence through grid battery 21 in wire 14. Across the wires 8, 10, is tuning condenser 22.

The receiving set comprises a receiving element 25, such as an antenna or other suitable receiving element having inductance 26, condenser 27 leading to ground 4. Coupled thereto is inductance 28 having tuning condenser 29, one end of inductance 28 being connected to grid 30 of receiving tube 31 and the other end being connected by wire 32 to filament 33. 34 is a heating battery connected to the filament through adjustable resistance 35. 36 are the telephone receivers in series with plate battery 37 in the circuit containing inductance 38 coupled to coil 26 and thence connected by wire 39 to plate 40. 41 is the key of standard wire telegraph pattern having a back contact 42 connected by wire 43 to compensating condenser 44, the other side of which is connected to the grid 30. Cooperating with back contact 42 is contact 45 connected by wire 46 to wire 32. The function of condenser 44 is to vary or suppress the beat note in the receiving set when contacts 42 and 45 are closed. The normal receiving position is with contacts 42, 45, open and the key preferably closed on the other side, as will now be described.

Leading from the antenna circuit 1 between inductance 2 and condenser 3 is wire 48 containing an adjustable condenser 49 connected by wire 50 to armature 51 of relay magnet 52. 53 is a stationary contact connected to the ground and the magnet 52 is supplied by battery 54 in wire 55 leading to contact 56 cooperating with contact 57 carried by key 41, contact 57 being connected to ground by wire 58.

When the key 41 is down, closing contacts 57, 56, magnet 52 is energized to draw down armature 51 and throwing compensating condenser 49 into the antenna circuit in parallel with condenser 3. The antenna circuit is tuned by condensers 22, 3 and 49, so that with condenser 49 in circuit, the desired frequency of oscillations is radiated through antenna 1, and in conjunction with the oscillations in the receiving set at the other station form the local signal oscillations there which are detected by the operator. When contacts 56, 57 are open the antenna either does not radiate at all, or radiates such different oscillations as to produce at the other station no beat note or a beat note of different frequency than the normal signal beat note. Thus the opening (actuation from sending position) of a key at either station, not only varies or suppresses the local beat note signal oscillations at that station, but also those at the other station.

In a system wherein the key is normally, for example, closed for receiving, (sending position), it will be seen that a cut in will be

produced at the other station by the lifting of the key. Each operator hears the characteristic beat note, the receivers having been tuned to give the best or the desired beat note with contacts 42, 45 open, so that opening of either key detunes both the receiver and transmitter at that station and destroys the beat note at the other station by causing it to be out of tune or out of audibility range, or rendered inaudible by the weakening of the radiated power owing to the detuning of sending circuit caused by the condenser 49 being cut out. Where I speak of varying the beat note to indicate a cut in I mean to include either partial or complete suppression of the beat note, or changing it from normal to abnormal within or without the audibility range, as one or the other result may be desirable according to the system in which the invention is used.

By this invention, a cut in at any time permits traffic to be handled much more rapidly and accurately, and the sending operator can hear his own message. This is because the beat note caused by the difference between the incoming and the local oscillation is audible at both stations, and the operator desiring to cut in, can do so by opening his key, which the sending operator will recognize. The same result occurs if a chopper or other well known means produces the local oscillation at the receiving station. The principle of the invention is applicable in various ways and to various circuits, and I do not restrict myself to the circuits shown herein except as limited by the appended claims.

This application is a division of my application filed February 8, 1918, Ser. No. 215,996, patented May 24, 1921, #1,379,144.

What I claim is:

1. In a radiotelegraph system, two stations each having means for producing, radiating and receiving oscillations of such difference in frequency as to simultaneously produce a signal current at each station, detecting means at each station for the signal current, the radiating and receiving means at at least one of said stations being separated, and a key at each station for varying both signal currents.

2. A radiotelegraph system comprising a station having radiating means, separate receiving means including a source of oscillations which combine with the received oscillations to produce a signal current, detecting means for the signal current, and a sending key so connected as to control the oscillations radiated from the radiating means to transmit signals and to effect like signals in the receiving and detecting means.

3. The method of effecting two way space radiotelegraphy which consists in producing at each of two stations outgoing and receiving oscillations of different frequency,

transmitting the outgoing oscillations and independently receiving the incoming oscillations at each station in a manner to produce signal oscillations at each station by

5 the resultant of the incoming and receiving oscillations without affecting the received by the outgoing oscillations, detecting such signal oscillations at each station to produce an indication, and varying 10 the outgoing oscillations at one station to effect a signal at the other station.

4. The method of effecting two way space radiotelegraphy which consists in separately producing at each of two stations outgoing and receiving oscillations of different frequency, transmitting the outgoing oscillations and independently receiving the incoming oscillations at each station in a manner to produce signal oscillations at 15 each station by the resultant oscillations of the incoming and receiving oscillations without affecting the received by the outgoing oscillations, detecting such signal oscillations at each station to produce an indication and varying the outgoing and receiving oscillations at one station to effect 20 a signal at both stations.

5. The method of effecting two way space radiotelegraphy which consists in separately producing at each of two stations outgoing and receiving oscillations radiating outgoing oscillations and independently receiving incoming oscillations, combining the incoming oscillations with the receiving 25 oscillations, there being such difference in frequency between the incoming and receiving oscillations as at each station to produce signal oscillations at each station, detecting such signal oscillations at each station to produce an indication, and simultaneously 30 varying the outgoing and receiving oscillations at one station to effect a signal at both stations.

6. In a radiotelegraph system employing a radiating element, and a receiving element spaced therefrom to prevent paralyzis, means for selectively producing outgoing oscillations on different frequencies, means for selectively producing receiving oscillations on different frequencies to be combined with incoming oscillations, means for detecting the incoming oscillations, and control means for both said producing means adapted to permit the simultaneous change 55 in frequency of the outgoing and receiving oscillations.

7. A space radiotelegraph system comprising a plurality of stations each having a radiating element and a receiving element separated to avoid paralyzis, means for causing said radiating element to radiate continuous oscillations and for independently receiving oscillations in the circuit of said receiving element, means at each station to detect incoming oscillations, and a key con-

trolling both the outgoing oscillations and the detecting means to enable simultaneous radiation of oscillations and reception of incoming signals with the key in determined position, said key also controlling the transmission of signals. 70

8. A space radiotelegraph system comprising a plurality of stations each having a radiating element and a separate receiving element, means for causing said radiating element to radiate continuous oscillations and means for generating continuous receiving oscillations in the circuit of said receiving element, there being such difference in the incoming and receiving oscillations at each station as to produce at each station continuous signal oscillations, and a key at each station controlling both signal oscillations in such manner that said oscillations are locally manifest only when the keys are in like positions, whereby to permit sending from one station and cut in from the receiving station upon actuation of each key respectively. 85

9. A space radiotelegraph system comprising a plurality of stations each having a transmitting antenna and a separate collecting element for receiving incoming oscillations, a source of outgoing oscillations coupled to the antenna, means for producing local receiving oscillations in the circuit of said collecting element, there being such difference in the received and local oscillations at each station as to continuously produce local signal oscillations and a key at each station controlling both signal oscillations in such manner that said oscillations are locally manifest only when the keys are in like positions, whereby to permit sending from one station and cut in from the receiving station upon actuation of each key respectively. 100

10. A space radiotelegraph system comprising a plurality of stations each having a transmitting antenna and a separate collecting element for receiving incoming oscillations, a source of outgoing oscillations coupled to the antenna, means for producing local receiving oscillations in the circuit of said collecting element, there being such difference in the received and local oscillations at each station as to continuously produce local signal oscillations at each station, means for detecting said signal oscillations, and a key adjacent the receiving set at each station controlling both signal oscillations in such manner that said oscillations are locally manifest only when the keys are in like positions, whereby to permit sending from one station and cut in from the receiving station upon actuation of each key respectively. 115

11. A space radiotelegraph system comprising a plurality of stations each having a transmitting antenna and a separate col-

lecting element for receiving incoming oscillations, and a source of outgoing oscillations coupled to the antenna, means for producing local receiving oscillations in the circuit of said collecting element, there being such difference in the receiving and local oscillations at each station as to continuously produce local signal oscillations at each station, means for detecting said signal oscillations, and a key adjacent the receiving set at each station connected to vary the local signal oscillations thereat and by distant control to simultaneously vary the outgoing oscillations from the radiating element, to effect a signal at both stations.

12. A space radiotelegraph system comprising a plurality of stations each having transmitting antenna and a separate collecting element for receiving incoming oscillations, a separate source of outgoing oscillations coupled to the antenna, means for producing local receiving oscillations in the circuit of said collecting element, there being such difference in the received and local oscillations at each station as to continuously produce local signal oscillations at each station, means for detecting said signal oscillations, and a key at each station for varying the capacity of both the antenna circuit and the receiving circuit simultaneously, whereby to permit sending from one station and cut in from the receiving station upon actuation of each key respectively.

13. A space radiotelegraph system comprising a plurality of stations each having means for producing local receiving oscillations and radiating outgoing oscillations, at least one of said stations having separate sources of outgoing and local receiving oscillations, and separate radiating and collecting elements, separated to prevent paralysis of the receiving circuits by the radiating means, there being such difference in the received and local oscillations at each station as to continuously produce local signal oscillations at each station, means for detecting said signal oscillations, and

a key at each station controlling both signal oscillations in such manner that said oscillations are locally manifest only when the keys are in like positions, whereby to permit sending from one station and cut in from the receiving station upon actuation of each key respectively.

14. A duplex radiotelegraph station employing a radiating element and transmitting means connected thereto, a separate element for collecting incoming signal oscillations, detecting means, said transmitting means being arranged so as not to interfere with the detecting means, and a transmitting key controlling the detecting means in such manner that incoming signal oscillations can only be normally detected and outgoing oscillations radiated when the key is in sending position.

15. A duplex radiotelegraph station employing a radiating element and transmitting means connected thereto, a separate element for collecting incoming signal oscillations, detecting means, said transmitting means being arranged so as not to interfere with the detecting means, and a transmitting key controlling both the transmitting and detecting means in one position so that reception is only had when the key is in sending position.

16. A duplex radiotelegraph station employing sending and receiving means connected to radiating and collecting elements respectively, and separated sufficiently to prevent paralysis of the receiver, a signal indicating device, a sending telegraph key controlling the incoming signal device in such a manner that incoming signals are only evident when the key is in closed sending position, so that in sending an operator hears his own sending, cut in being afforded by the suppression of the incoming indication by opening the key.

Signed at New York in the county of New York and State of New York this eleventh day of April, A. D. 1921.

PAUL WARE.
